CHARLES S. CHAFFEE AND CHARLES H. VANDERCOOK, OF BIRMINGHAM,
CONNECTICUT.

Design No. 2,947, dated March 10, 1868.

DESIGN FOR A HOOP-SKIRT.

The Schedule referred to in these Letters Patent and making part of the same.

TO ALL WHOM IT MAY CONCERN:

Be it known that we, CHARLES S. CHAFFEE and CHARLES H. VANDERCOOK, of Birmingham, in the county of New Haven, and State of Connecticut, have invented a new Design for Hoop-Skirts; and we do hereby declare the following, when taken in connection with the accompanying drawings, and the letters of reference marked thereon, to be a full, clear, and exact description of the same, and which said drawings constitute part of this specification, and represent, in—

Figure 1, a side view of a hoop-skirt complete, and, in

Figure 2, a section of a spring enlarged.

This invention relates to a design for a skirt formed from metallic hoops attached together by tapes or cords, and consists in the corrugation of the several hoops, whereby the beauty of the skirt is very greatly enhanced.

To enable others to understand and produce our design, we will proceed to describe the same as illustrated in the accompanying drawings.

The several hoops are cut to their proper length in the usual manner, and passed between suitable rollers or dies, which corrugate the several hoops, as denoted in fig. 1, more clearly seen in an enlarged view of one of the springs. After being thus formed, the hoop-skirt is formed from the several springs in the usual manner.

Having thus fully described our invention, what we claim as new, and desire to secure by Letters Patent, is—

The design for hoop-skirts, as herein illustrated and described.

CHAS. S. CHAFFEE,
CHAS. H. VANDERCOOK.
